UNITED STATES PATENT OFFICE.

MAX L. SCHLUETER, OF CHICAGO, ILLINOIS.

FLOOR-SURFACING MACHINE.

No. 882,847.

Specification of Letters Patent. Patented March 24, 1908.

Application filed March 21, 1907. Serial No. 363,531.

To all whom it may concern:

Be it known that I, MAX L. SCHLUETER, a citizen of the United States, residing in Chicago, in the county of Cook and State of Illinois, have invented a new and useful Improvement in Floor-Surfacing Machines, of which the following is a specification.

This invention relates to floor surfacing machines, and its object has been the production of an efficient machine having an electric or other motor for operating its surfacing drum, and yet made small enough and light enough to permit its being propelled by manual power. It is so constructed that its drum is normally lifted from the floor by spring power, but may be easily lowered into acting position by raising the propelling handle so as to tip the machine on its supporting wheels, and, as a result of this feature, the drum need never cut hollows in the floor because it is automatically raised so it cannot do so the moment the operator lets go of the handle. In other words, the drum, although it is continuously operated, is rendered idle and prevented from doing harm to the floor whenever the machine stops in its movement over the floor.

The machine also embodies other features of importance, and its nature is fully disclosed below and also in the accompanying drawing, in which latter

Figure 1 is a side elevation. Fig. 2 a plan, omitting the dust collecting bags, and Fig. 3 is a rear view of the invention. Fig. 4 is a section on line 4-4 of Fig. 1. Fig. 5 is a vertical section of one of the drum bearings, and Fig. 6 is a section of one of the spring casters.

In said drawing 10 represents the frame of the machine, supported by the wheels 11 and their axle 12 and by the casters 13 and their springs 14. The propelling handle 15 is attached at any convenient point, preferably to the table 16 carrying the controlling switch 17 and the graduated contacts 18 of the starting devices of the electric motor 19. This table is supported in any suitable way from the frame 10. It will be noted that the caster wheels are forward of the center of the machine and the wheels 11 back of it, and that the machine may be easily tipped on said wheels by applying power to the handle. The caster wheels have their stems extending upward into partially hollow bearings 20, and the stems are threaded and provided with nuts 21 whereby the blocks 22 at the

lower end of the bearings are supported. On the blocks 22, ball bearings may be formed for the collars 23 rigid on the pivots, such collars sustaining the weight. The springs 60 14 are confined in the bearings between the solid centers 24 and the collars 23, and the pivots are loose in said centers and also in the blocks 22. The bearings 20 are threaded exteriorly and engage threads in a base 25 65 secured to the frame 10. By turning the bearings 20 the action of the springs 14 may be regulated and the machine raised or lowered, as will be understood.

19 is the electric motor and 31 is the shaft 70 driven by it. On this shaft is a pulley 32, through which and the belt 33 and pulley 34 the fan for drawing the dust from the surfacing drum is actuated. Said shaft also carries a sprocket wheel 35 and through such 75 sprocket wheel, the sprocket chain 36 and the sprocket wheel 37 drives the surfacing drum 38. This drum may be of the ordinary construction and covered with sandpaper or its equivalent, and the pipe 39 is adapted to 80 carry away the dust given off from it and carry it to the fan by which it is forced into the dust bag 40. A hood 41, hinged at 42, is placed over and covers the top and front of the drum, and prevents the escape of the dust. 85

At its ends the drum is provided with bearings supported in the side plates 43. These plates are bolted to side plates 44 formed on the main frame, and are capable of being removed whenever it is desired to 90 take out the drum. The bolt openings 45 in them are also elongated horizontally, so that the plates may be adjusted whenever necessary to take up slack in the chain 36. The drum bearings in these plates are each 95 provided with springs 46 and 47 one above and the other below the drum journal, so that the drum is adapted to yield whenever it passes over an unevenness or obstruction on the floor, and also to enter depressions 100 in it, and the depth of its action on the floor and the freedom of its vertical movements may be regulated as desired by the screw 48 bearing upon the upper spring and adapted to compress both springs. The bearing is 105 also adapted to rock as will be seen from Fig. 5 when one end of the drum descends into a depression or rides over a projection, which does not extend under the other end. The standards 50 are adapted to support 110 the electric wires by which the motor is operated. Two are provided as a matter of

convenience, one on either side of the machine.

In operating the machine, the electric current is first turned on, and the drum got under way. The attendant then raises the handle sufficiently to carry the drum down upon the floor, and moves the machine either forward or back as necessity requires. When he wishes to stop surfacing, he either releases the handle wholly or allows it to rise to its normal position, when the drum will be immediately lifted out of its acting position by the springs of the casters.

I claim:

15 1. A floor surfacing machine provided with a surfacing drum, a motor for actuating the drum, a pair of supporting wheels, and a propelling handle, the drum and the handle being located upon opposite sides of the 20 supporting wheels so that the drum may be depressed by lifting on the handle, the portion of the machine in which the drum is mounted being provided with means whereby it may be automatically lifted when pressure upon the handle is withdrawn.

2. The surfacing machine having a surfacing drum at one end normally supported above its acting position by springs, centrally located supporting wheels upon the 30 axle of which the machine may be tipped to carry the drum into or out of action, a motor for said drum located over said

wheels, and a handle at the other end of the machine adapted both to propel the machine and to depress the drum into action.

3. The surfacing machine provided with a surfacing drum, a tipping frame in one end of which the drum is mounted on yielding bearings, a pushing handle at the other end of the frame, and yielding caster supports 40 under the drum end of the frame, whereby the vibrations imparted to the drum are absorbed.

4. The surfacing machine having carrying wheels upon which it may be tipped, a surfacing drum at one end, a motor driving said drum, located over said wheels but independent thereof a handle at the other end by raising which the drum is lowered into action, and springs by which the drum 50 is kept out of action when the operator is not lifting on the handle.

5. The surfacing machine the surfacing drum whereof is provided with spring-supported bearings allowing either end of the 55 drum to drop or rise without the other, and thus conform to the inequalities of the floor and screws 48 bearing upon and regulating the action of the springs.

MAX L. SCHLUETER.
